UNITED STATES PATENT OFFICE.

JOHN EDWARD ANGER, OF PRESTON, ENGLAND.

STREET-CAR INDICATOR.

No. 904,916.

Specification of Letters Patent.

Patented Nov. 24, 1908.

Application filed February 7, 1908. Serial No. 414,721.

To all whom it may concern:

Be it known that I, JOHN EDWARD ANGER, citizen of the United States of America, residing at Preston, in the county of Lancaster, in the Kingdom of England, works manager, have invented certain new and useful Improvements in Street-Car Indicators, for which application has been made in Great Britain, No. 15,254, dated July 2, 1907.

10 This invention has for its object a route or destination indicator for trams and other purposes of the type in which two rollers are driven by one handle which actuates either according to the direction 15 in which the handle is turned without the use of spring rollers.

In the accompanying drawings:—Figure 1 is a part front elevation of a route or destination indicator constructed in accordance 20 with my invention; Fig. 2, a horizontal section on the line $\alpha-\beta$ of Fig. 1; Fig. 3, an inverted plan view of the lower ratchet wheel and a portion of the operating handle.

In carrying the invention into effect, I 25 provide the usual flexible screen A of suitable material having the various routes or destination names printed thereon, and connected at its ends to carrying rollers B B'. These rollers are journaled in metal bearings at one end, and at the other fit on to the squared end C of spindles D D' by which they are rotated, so as to wind the screen A from one roller on to the other. One spindle D' is geared to a vertical spindle E by miter 30 wheels F, and the other spindle D is geared to a sleeve G mounted on the said spindle E by another pair of miter wheels F'. On the bottom end of the vertical spindle is secured a ratchet wheel H, and at the bottom end 35 of the sleeve G is secured another ratchet wheel H' with its teeth arranged the opposite way, and between these ratchet wheels, I place a crank handle J mounted loosely 40 on the spindle E so that it will have considerable play sidewise. This play is provided for by the hole P being larger than the 45 spindle E.

The handle J is provided with fangs or fingers K L projecting in opposite ways and 50 in different planes, so that one will engage the teeth of one ratchet wheel H' and the other the teeth of the other ratchet wheel H. If the handle J be turned one way, one fang 55 K will engage in one ratchet wheel, while the other fang L will slip over the teeth of the other wheel, the side play of the

handle on the spindle permitting of this. Thus the rotation of the handle J will engage one of the ratchet wheels H, and so turn the rollers one way, and wind the screen 60 on to one roller B' from off the other roller B. If however the handle be turned the reverse way, one fang will come out of engagement with its ratchet wheel and the other fang will come into engagement with the 65 other ratchet wheel, the play of the handle on the spindle permitting of this. This locks the crank handle in gear with the sleeve G which is in gear with the other carrying roller B and winds the screen the reverse 70 way: By rotating the handle J in the first mentioned direction, one carrying roller B will run idle, but the other roller B' will be turned. Rotating the handle J in the other direction will have the opposite effect, and 75 the roller B which before ran idle, will now be driven and roller B' will run idle. Thus in order to cause any one of the different terminals on the route to appear, the operator turns the handle J one way, thus winding the screen A more or less from one roller 80 on to the other. To wind the screen back again he turns the same handle in the other direction. The end of the spindle E is provided with a cap M fastened on by means 85 of a pin. The longitudinal movement of the vertical spindle is prevented by means of a suitable two-armed bracket N, the lower miter wheel F' resting on the lower arm, and the upper one F resting on the upper 90 one. The sleeve G, moreover, is by preference made in two lengths, one of which is made as a part of the lower miter wheel F' and the other as part of the ratchet wheel H', so that when fitting the device in position, the sleeve which has a miter wheel F' attached, can be slid in from the top, and then the other part of the sleeve which has the ratchet wheel H' secured to it, is passed up from below the canopy Q, the two adjacent ends where they meet, being locked 95 together by means of a clutch O.

I declare that what I claim is:—

1. In a route or destination indicator in which rollers carry and operate an indicating screen, a spindle having a drive wheel thereon, a sleeve on the spindle provided with a second drive wheel and a handle mounted loosely on the spindle, provided with sets of fangs or fingers projecting in different ways, one adapted to engage one drive wheel in the movement of the handle 105.

in one direction, and the other adapted to engage the other drive wheel in the movement of the handle in the other direction, substantially as described.

5 2. In a route or destination indicator, of that class in which rollers carry and operate an indicating screen, the combination comprising a spindle for turning one roller with a drive wheel fast thereon, a sleeve mounted 10 on the said spindle for turning the other roller with a drive wheel fast thereon, a crank handle mounted loosely on the spindle, fangs or fingers on the crank handle projecting in different ways and in different planes, 15 one to engage one drive wheel and the other to engage the other drive wheel, and so arranged that if the handle be turned one way one set of fangs will engage the opposing teeth of one drive wheel, or if turned the reverse way the fangs will come out of engagement and the other fangs enter into engagement with the opposing teeth on the other drive wheel, substantially as described.

3. In a route or destination indicator of 25 that class in which rollers carry and operate an indicating screen, the combination with the spindle for turning one roller, the sleeve mounted thereon for turning the other roller, and gear wheels fixed respectively on the

spindle and the sleeve, of a two-armed 30 bracket so arranged that the one gear wheel rests on the one arm and the other gear wheel rests on the other arm, substantially as described.

4. In a route or destination indicator having rollers and an indicating screen operated thereby, the combination with the spindle for turning one roller, of a sleeve mounted thereon to turn the other roller, said sleeve being made in two lengths, one of which is 40 made as part of the gear wheel and the other as part of the drive wheel, and a clutch for locking the adjacent ends of the sleeve together, the arrangement being such that when fitting the device in position, the 45 sleeve which has the gear wheel attached, can be slid in from the top, and the other part of the sleeve which has a drive wheel secured to it, is passed up from below, and the meeting ends locked together, substantially as 50 described.

In witness whereof, I have hereunto signed my name this 24th day of January 1907, in the presence of two subscribing witnesses.

JOHN EDWARD ANGER.
